Des. 232,175
Patented July 23, 1974

232,175

SUPPORT FOR THE HEATING ELEMENT OF A RADIANT HEATER OR THE LIKE

Ralph Santoro, Verona, Pa., assignor to Emerson
Electric Co., St. Louis, Mo.

Filed May 5, 1972, Ser. No. 250,843

Term of patent 14 years

U.S. Cl. D23—127 Int. Cl. D23—03

FIG. 1.

FIG. 2.

FIG. 3.

FIG. 4.

FIG. 5.

FIG. 6.

FIG. 7.

FIG. 8.

FIG. 9.

FIG. 10.

FIG. 1 is an edge view of a support for the heating element of a radiant heater or the like showing my new design;

FIGS. 2 and 3 are respectively left and right side elevational views thereof,

FIGS. 4 and 5 are perspective views showing opposite sides of the support,

FIG. 6 is an edge view of a second embodiment of my new design,

FIGS. 7 and 8 are respectively left and right side elevational views thereof.

FIGS. 9 and 10 are perspective views showing opposite sides of the support shown in FIGS. 6 through 8.

I claim:

The ornamental design for a support for the heating element of a radiant heater or the like, substantially as shown and described.
